UNITED STATES PATENT OFFICE

SALVATORE LIGAMMAR, OF CHICAGO, ILLINOIS, AND BERNARD DALLIO, OF LODI, NEW JERSEY.

ALARM MECHANISM.

Application filed October 1, 1921. Serial No. 504,810.

To all whom it may concern:

Be it known that we, SALVATORE LIGAMMAR and BERNARD DALLIO, citizens of the United States of America, residing at Chicago and Lodi, in the counties of Cook and Bergen and States of Illinois and New Jersey, respectively, have invented new and useful Improvements in Alarm Mechanism, of which the following is a specification.

10 This invention relates to alarms and more particularly to burglar alarms.

An object of this invention is the provision of an alarm mechanism which may be conveniently attached to a door or closure, 15 and when so attached, the same may be set as to give an alarm, should an attempt be made to force an entrance.

Another object is the provision of an alarm mechanism which may be made inoperative by an authorized person should it be desired to open said door or closure.

Another object of the invention is the provision of an alarm mechanism including an alarm box, said alarm box having means for 25 automatically firing a number of blank cartridges, successively.

With these and other objects in view, the invention resides in the novel construction and arrangement of parts, the essential features of which are hereinafter fully described, are particularly pointed out in the appended claims and are illustrated in the accompanying drawings, in which:—

Figure 1, is a side elevation of a door and 30 jamb showing the invention applied thereto.

Figure 2 is a view of the alarm mechanism with the cover removed, showing parts in section.

Figure 3, is a vertical section on the line 40 3—3 of Figure 2.

Figure 4, is a detail section on the line 4—4 of Figure 1.

Figure 5, is a view similar to Figure 2, showing a slightly modified form of the 45 alarm mechanism.

Figure 6, is a vertical section on the line 6—6 of Figure 5.

Like characters of reference refer to like parts in all views.

50 In the drawings, the numeral 10 indicates a door or closure and 11 the jamb, to which the invention is shown applied thereto. Attached to the inside of the door 10, by any suitable means is an alarm box 12, having a swinging cover 13 to allow access to

the alarm mechanism which will now be described.

Enclosed in the alarm box 12 is a plate 14 the same being pivoted in the side walls of the box as at 15. Slots 16—16 are provided in the plate 14 for the reception of bolts 17—17 carried by the rear wall of the box 12, washers 18 and nuts 19 are received by the bolts 17—17. Fastened to the plate 14 are flat springs 20, the extremities of which are extensions 21, said extensions terminating in fingers 22, the fingers 22 being of different lengths for the purpose to be presently described. A firing pin 23 is formed on the underside of the extensions 21. A trigger 24 is pivoted as at 25 to the box 12. A spring 26 is secured to the trigger 24 and to one of the bolts 17. A lip 27 is formed on the trigger 24. Engageable with the lip 27 is a hook 28 formed on one extremity of a rock arm 29, the opposite end of said rock arm extending out through a slot 30 in the box 12, and carrying a roller 31. A spring 32 constantly forces the hooked end 28 upward for engagement with the lip 27. The rock arm 29 is mounted on a slide 33 as at 34, said slide being fastened to a latch bar 35 controlled by a lock mechanism 36 of the usual construction. A bolt 37 is secured to the latch 35, the same adapted to enter a keeper 38. The bolt 37 is weakened as at 39 for the purpose to be presently described.

Secured to the jamb 11 is what I shall term, a cam plate 40 having a cam surface 41 which receives the roller 31 of the rock arm 29.

In the operation of the device, should it be desired to set the alarm, the nuts 19 and washers 18 are first removed from the bolts 17 and the plate 14 carrying the springs 20 swung out so that the fingers 22 will engage with the trigger 24. The cartridges 42 are then inserted in the openings 43 in the rear wall of the casing 12. This being done the washers 18 and nuts 19 are placed back on the bolts 17 and screwed down as shown in Figure 3. By screwing the plate 14 down against the rear of the box 12 the springs 20 will be placed under tension. During this procedure the latch 35 has been in retracted position and a dog 44 engaging the lip 27. A key is now inserted in the lock 36 and the bolt 37 enters its keeper 38 and at the same time the hook 28 engages

the lip 27, dog 44 is moved out of engagement with the lip 27 and the roller 31 is brought into engagement with the cam plate 40.

5 It will be readily seen that should an entrance be forced by some unauthorized person, the bolt 37 will bend or break at its weakened portion 39. As the door 10 moves inwardly, the roller 31 will ride upwardly 10 on the cam surface 41 of the cam plate 40 and in so doing will move the rock arm 29 downwardly, thereby moving the trigger 24, which in turn, releases the fingers 22 therefrom, allowing the firing pins 23 to discharge the cartridges 42, successively.

15 Should an authorized person desire to open the door 10, it is only necessary to insert the necessary key and retract the latch 35 which will render the device inoperative, as

20 will be readily seen.

In Figure 5, I have shown a slightly modified form of the firing means which consists of a block 50 removably secured to the rear wall of the box 12 in the same 25 manner as the plate 24 in the preferred form. The block 50 includes a number of bores 51 in which are arranged the firing pins 52. Springs 52' are interposed between the pins 52 and a wall 53 of the block 30 50. Secured to the pins 52 and extending through slots 54 in the block are fingers 55 engageable with the trigger 24. The operation of this form is similar to the preferred form in that the trigger 24 releases the fingers 55, thereby allowing the springs 52 to force the firing pins 52 into contact with the cartridges.

Having described what we consider the preferred form of our invention, we want 40 it to be understood that the device may be placed on windows and other closures should the same be desired; also that changes, alterations and modifications which fall within the appended claims may be resorted to 45 when so desired.

What is claimed as new is:—

1. In a device of the class described, the combination of a closure member and a stationary member, an alarm mechanism secured to said closure member including a plurality of cartridges, a plurality of movable firing pins adapted to co-act with the said cartridges, and means for holding the pins in set position, means operative upon 50 the opening of the closure member for actuating said first mentioned means to cause said firing pins to explode said cartridges seriatim, and a lever included in the alarm 55

mechanism and controllable by a lock for rendering said last mentioned means operative and inoperative.

2. An alarm mechanism for swinging doors comprising a resilient firing pin, movable means for holding the pin in set position including a rocker member, a bolt; co-acting with said movable means, a lock coacting with the bolt, and means adapted to be secured in fixed relation to the door and coacting with said rocker so as to actuate said rocker to release the setting means when the door is opened aside from legitimate actuation of the bolt, means for positioning a detonator in co-acting relation to the firing pin, the connection between the rocker and said bolt serving to release the rocker from said setting mechanism on legitimate actuations of the bolt.

3. An alarm mechanism adapted to be secured to a closure member comprising a housing, a plurality of spring pressed firing pins mounted therein and normally held in operative position by means of a trigger, a plurality of detonators, a rocker engaging said trigger and operative by means of a cam adapted to be secured to a stationary member for releasing said firing pins seriatim.

4. An alarm mechanism adapted to be secured to a closure member comprising a casing, a plate pivoted in said casing, a plurality of spring pressed firing pins mounted on said plate and normally held in operative position by means of a trigger, a plurality of detonators, a slide mounted in said casing, a lever pivoted on said slide and held in engagement with the trigger when the same is in operative position, and means secured to a stationary member for engagement with the lever for releasing the detonators seriatim.

5. An alarm mechanism adapted to be secured to a closure member comprising a housing, a plurality of spring pressed detonators, mounted therein and normally held in operative position by means of a trigger, 105 a rocker engaging said trigger and operative by means of a cam adapted to be secured to a stationary member for releasing said detonators seriatim, a key controlled bolt co-acting with said trigger engaging 110 means for rendering the device operative and inoperative.

In testimony whereof we have affixed our signatures.

SALVATORE LIGAMMAR.
BERNARD DALLIO.
